AUTOMATIC TRAFFIC DIRECTING DEVICE
FOR GARAGES

Philip H. Burn, Forest Hills, N. Y.

Application November 14, 1946, Serial No. 709,769

11 Claims. (Cl. 177—311)

1

My invention relates to garages, and in particular to a novel means for the more efficient handling of traffic in garages.

With the growing problems of traffic congestion in large cities and of rising labor costs in the staffing of garages located in such cities, it is becoming desirable, if not necessary, to devise means for handling the maximum number of vehicles in off-the-street parking with a minimum of personnel.

It is, accordingly, an object of my invention to provide improved means for the handling of vehicular traffic in a garage.

It is another object to provide an improved traffic-control system for garages that will reduce the required number of operating personnel, that is, to provide a garage which will be virtually "self-parking."

It is a more specific object to provide novel computing and indicator means for routing traffic to a first area until that area becomes saturated, and then automatically to route the traffic to another area.

Other objects and various further features of the invention will be pointed out or will occur to those skilled in the art from a reading of the following specification in conjunction with the accompanying drawings, in which:

Fig. 1 schematically indicates in perspective a more or less conventional garage to which my traffic-control system is shown adapted;

Fig. 2 is an enlarged detail view in perspective illustrating a portion of my control system, as applied to the garage of Fig. 1;

Fig. 3 is a partially sectionalized side view of a computing device shown associated with suitable counters and indicators according to the invention;

Fig. 4 is a view in perspective schematically illustrating application of my invention to another type of garage;

Fig. 5 is a block diagram schematically illustrating the interrelation of computers and indicators for the garage of Fig. 4;

Fig. 6 is a fragmentary view in perspective schematically illustrating application of my invention to still another type of garage;

Fig. 7 is a schematic wiring diagram for electrical connections in the garage of Fig. 1; and

Fig. 8 is a similar diagram for the garage of Fig. 4.

Broadly speaking, my invention contemplates a system of computers and indicators applied to a garage having a plurality of independently accessible parking areas. In general, a first

2

counting means is employed to count the number of vehicles entering a first parking area, a second counting means similarly counts the number of vehicles leaving said first parking area, a computer resolves the difference between the number of operations of both said counting means, and a traffic-routing indicator responds to the output of the computer so as to route traffic to a different parking area when the computing device determines that the first parking area has been substantially filled. In the specific forms to be described, additional counting devices are associated with those covering particular parking areas in order to indicate automatically when the whole garage (including all parking areas) has been filled. The computer means may be any means for resolving the difference between two functions, and in the form to be described it is a more or less conventional gear-type differential mechanism.

Referring to Figs. 1, 2, and 3 my invention is shown in application to a more or less conventional garage having a plurality of parking areas which may be identified as separate floor levels 25 10, 11, 12 and 13. All floor levels are accessible from a single entrance 14 and communicate to a single exit 15 through a system of up-ramps 16, 17, 18 and a system of down-ramps 19, 20, 21, as will be clear from noting the directional arrows 30 on these ramps.

In accordance with the invention, each parking area or floor is provided with an in-counter 22 for counting vehicles entering the area and with an out-counter 23 for counting vehicles leaving the area. The counters 22—23 may be mechanical switches stretching across the floor of the entrance lane, or any other suitable arrangement. In the form shown, however, they are conventional photoelectric counters responsive to the 35 simultaneous interruption of twin light beams projected between counter boxes 22' and 22'', and between counter boxes 23' and 23'', as the case may be. Preferably, the spacing between beams of light is such as to prevent operation of the 40 counter device by light pedestrian traffic but to permit the generation of an electric counting impulse upon the simultaneous interruption of both beams, as by a passing vehicle.

In the form shown, the counting devices 22—23 45 supply counting impulses to operate solenoid-actuated ratcheting devices coupled to the two differential parts of a computing mechanism 24. The in-counter 22 is connected to operate a solenoid 25, which in turn may index a ratchet wheel 26 one ratcheting position for each impulse sup-

plied. In like manner, the solenoid 27, which is connected to out-counter 23, may index another ratchet wheel 28 one ratchet position for each out-counter impulse. The differential computer may be a conventional arrangement comprising two driven bevel gears 29-30 and idler or output bevel-gear means 31, all gears being carried and suitably supported by a yoke or housing 32. Since the ratchet wheels 26-28 are connected to rotate the gears 29-30 in opposing senses, the differential between these motions may be observed in the resulting displacement of the yoke or housing 32. In the form shown, the housing 32 carries a projection or lug 33 for engagement with an electric switch 34 to control the operation of a traffic-control indicator 35.

The parts which have been described may be suitably designed to cause a single rotation of the housing 32 for a counter differential representing the entire capacity of a given parking area, say for the floor 10, but in the form shown the parking areas have greater capacity than can be accommodated in a single rotation of the yoke 32. Accordingly, the yoke 32 may be formed integrally with or secured as by a set screw 36 to a shank 37, threadedly engaging a support standard 38 for the differential system. With this arrangement, it will be appreciated that each rotation of the yoke 32 (representing a given increment in the differential between in-counter and out-counter operations) will be accompanied by a proportional axial advance of the differential mechanism and of its yoke 32. Suitably designed, the yoke may be axially displaced (right in the sense of Fig. 3) sufficiently to cause the lug 33 to trip the switch 34 when the parking area is saturated or substantially filled. In the arrangement shown this tripping of the switch 34 will be accompanied by extinction of the arrow 39 which directs traffic into the saturated parking area and by illumination or other operation of the signal 40 which directs traffic to another parking area.

Returning now to a consideration of my traffic-control system as applied to the entire garage, let it be assumed that it is desirable to fill lower floors or lower levels of parking before proceeding to fill the next upper level. In the garage of FIG. 1 then, the counter-computer-indicator system will direct traffic into the floor 10 until the differential system indicates that floor to be full or substantially full. Traffic will then be routed up the ramp 16 and into the floor 11. The counting, computing, and indicating process which has been described will then be repeated for the floor 11 until that floor is substantially full, at which time the computer for floor 11 will operate the traffic-control indicator to demand that traffic be routed up ramp 17 to floor 12. The process will be repeated again for floor 12 and for floor 13, as will be clear. It will be understood that should vehicles depart from one of the lower completely filled areas before the garage is filled on all floor levels, the computer 24 for that particular floor level will be caused to operate so as to return the lug 33 into operating engagement with the switch 34. Preferably, this return or reverse operation of the switch 34 takes place after several cars have left a full floor, so that the indicator 39 will not route traffic back on to that floor until there are several vacancies. This "insensitive" operation of the switch 34 may be accomplished by employment of a conventional toggle action in the switch 34.

In accordance with a further feature of the invention, additional means may be employed

near the entrance of the building to indicate whether or not the garage is filled to capacity. This additional function may be performed by appropriate series connection of the computers 5 or indicators for the several floors, but in the form shown a simple single in-counter 41 and out-counter 42 located at the entrance 14 and exit 15, respectively, will suffice. By designing the computing system to cooperate with the counters 10 41-42, a "Full" indicator 43 may be automatically operated when the computed differential represents a capacity load for the entire garage.

For a more detailed consideration of the operation, reference is made to FIG. 7. In FIG. 7, in- and out-counters 103-104 for floor 10 will be seen to operate a computing mechanism 105, which may be generally similar to that shown in detail in FIG. 3. The indicator 86 is connected to the computing mechanism 105, as shown for the indicator 35 in the computing mechanism of FIG. 3. For floor level 11 in- and out-computers 99-100 are connected to operate computer 106 and the indicator 87. For floor level 12, in- and out-counters 101-102 are connected to operate computer 107 and indicator 88. Finally, the main in- and out-counters 41-42 for the garage are connected to operate computer 108 and the full sign 43. In the form shown in FIG. 7, all three of the computers 105-106-107 may be the same 30 since the parking areas on floors 10-11-12 are substantially the same. Since computer 108 operates for the garage as a whole, it should be designed to function only when enough cars have been admitted to the garage to fill all parking 35 areas. Since the first three computers 105-106-107 cover three-quarters of the garage and since the computer 108 covers the garage as a whole, there need be no employment of such counters and computers for the top floor 13; this function 40 of monitoring the top floor 13 will be understood to be performed also by the counter 108.

Referring to FIGS. 4 and 5, my invention is shown in application to the routing of traffic through a so-called all-ramp garage, which may be of the type disclosed in the copending patent application Serial No. 661,964, filed April 13, 1946. For purposes of clarity, only one traffic system is included in the drawing (FIG. 4) but it will be appreciated that the principles to be discussed are 50 applicable to the multiple systems disclosed in the above-identified copending application. The single system shown comprises a plurality of intercommunicating inclines or ramps, flowing from an entrance 44 and into an exit 45. The entrance 44 and the exit 45 may open to succeeding parallel streets defining the block in which the garage is located.

The entrance 44 communicates to a down-ramp 46 and to an up-ramp 47. Exit from the down-ramp 46 is afforded by an end-aisle 48 communicating to an up-ramp 49 which leads directly to the exit 45. In the form shown, the down-ramp 46 and the up-ramp 49 are formed as one and the same floor surface; alternatively, they may be interleaved with other ramps, as disclosed in the above-identified patent application. The up-ramp 47 leads to another end-aisle 50 from which one has the option of proceeding upwards along 65 another up-ramp 51 or downward toward the exit along a down-ramp 52. The up-ramp 51 is shown to be similar to the lower ramps 46 and 49, in that it may be adjacent to another down-ramp 53. Both the ramps 51 and 53 communicate to a 70 landing 54 from which an up-ramp 55 ascends

to a landing 56. Exit from landing 56 is by way of a down-ramp 57 to the landing 54.

Assuming that it is desirable to fill to capacity all lower slopes of the garage of Fig. 4 before proceeding to fill the upper slopes, an indicator 58 may route traffic first into the down-ramp 46, or rather into the parking area comprising the down-ramp 46 and the up-ramp 49. In a manner similar to that which has been described for Figs. 1, 2, and 3, the parking area 46-49 may be monitored by a single in-counter 59 and by an out-counter 60, located respectively at the entrance and at the exit of this parking area. For purposes of simplifying the drawing, the counters shown in Fig. 4 are indicated schematically by lines extending transversely of the lane of traffic at the point to be monitored. The output of both counters 59 and 60 may be fed to a differential mechanism 61 such as that described in Fig. 3, and it will be clear that when the recorded differential represents the number of vehicles within the area 46-49 to be substantially the capacity of that area, the indicator 58 will be extinguished and a similar indicator 62 illuminated, thereby routing succeeding vehicles into the up-ramp 47.

Since the area represented by the up-ramp 47 includes a traffic aisle which must be used by all vehicles entering upon the upper ramps, it is not accessible independently of the other upper ramps and therefore need not be monitored by a separate counter-and-computing system. However, before traffic is routed from the end-aisle 50 up the up-ramp 51, it will be desirable to load the down-ramp 52—which is accessible independently of the up-ramps from ramp 51 on up. For this reason, it is desirable to incorporate an in-and-out counting system for the parking area on ramp 52. Since there are two sources of traffic feeding down-ramp 52, two in-counters 63-64 are employed—the counter 63 tabulating the number of vehicles passing along the end-aisle 50 from ramp 47 into ramp 52, and the counter 64 tabulating the vehicles coming from down-ramp 53 into ramp 52. Out-counting for the ramp 52 may be effected by a counter 65 located at the lower end of the ramp 52. Again, the proper evaluation of signals from counters 63, 64, 65 may be effected by a suitable computer mechanism 66 generally similar to that disclosed in Fig. 3. However, in the case of counters 63, 64, 65 the combined output of counters 63 and 64 is to be compared differentially with that from counter 65. It will be clear that this summation of the outputs of counters 63 and 64 may be effected by provision of an additional solenoid-actuated pawl 66' to operate the in-counting ratchet wheel for the computer 66, whereby impulses from either of counters 63 and 64 may result in an "in" indexing of the ratchet wheel. When the differential recorded by the computer 66 represents a full parking load for the ramp 52, the computer 66 will be operative to extinguish the traffic arrow 67 directing traffic down into ramp 52 and to illuminate the traffic arrow 95 calling for a flow into the up-ramp 51.

Again, the traffic aisle in the ramp 51 must be used by vehicles parking on that ramp and also by vehicles proceeding into other ramps above ramp 51. Ramp 51 is, therefore, like ramp 57, not independently accessible and, therefore, needs no counting monitoring.

Motorists who find no parking space on ramp 51 will first be directed by a traffic arrow 68 into the down-ramp 53, and in entering this down-

ramp they traverse an in-counter 69. Exit from the area of down-ramp 53 is monitored by the out-counter 64. It will be noted that, like ramp 52, ramp 53 is served by two separate lanes of incoming traffic—one via the end-aisle 54 from up-ramp 51, and the other from down-ramp 51. In order, then, to complete the in-counting function for ramp 53 another counter 70 may be located at the foot of the down-ramp 51. Counters 69 and 70 may then be suitably ganged (as by electrical connection in parallel, see Fig. 8) so that each supplies adding impulses to a computer 71 for the parking area 53. The computer function also includes subtraction of the counting impulses supplied by the out-counter 64. It will be clear that when a predetermined differential indication is resolved by the computer 71, so as to represent a full load on the ramp 53, the arrow 68, which points to the right at the top of ramp 51, will be extinguished and the arrow 72, which points to the left, toward the up-ramp 55, will be illuminated.

It will be appreciated that once the arrow 72 is illuminated, traffic will be routed up ramp 55 over the end-aisle 56 and down ramp 57 to fill the last remaining parking area in the garage. There remains, therefore, a need only for suitable means to indicate when the garage is full. As in the case of the Fig. 1 arrangement, a "Full" sign 73 may be operated by counters monitoring total entrance-traffic flow and total exit-traffic flow. In the form shown, all entrance-traffic passes an in-counter 74, and the total exit traffic may be determined from a summation of the impulses supplied by out-counters 60 and 65. The differential of the "in" and "out" counts derived from counters 74 and 60-65 may be resolved by a suitable computer 75 which will operate the "Full" sign 73 when the garage is filled to capacity. It will be understood that, when cars depart from the garage so as to make space available for further vehicles, one or both of the counters 60-65 will supply sufficient out-counting impulses to cause extinction of the "Full" sign. Furthermore, it will be clear that the correct traffic-routing signals will have been illuminated to conduct the new customers to the area in which they can find parking space—since customers leaving particular parking areas will automatically be counted out so as to show vacancies in those areas.

In Fig. 6 my invention is shown in application to still another type of garage having a plurality of independently accessible parking areas. The Fig. 6 arrangement is a so-called Z-type garage having a plurality of floor levels 76-77 (each split into halves, right and left in the sense of Fig. 6), with mezzanine floor levels 78-79 sandwiched therebetween. For the Z-type floors shown, traffic flow between floors will be substantially as follows. Incoming traffic will arrive on the left end of the lower floor 76 via up-ramp 80 and, once on floor 76 the motorist has the option of parking under the mezzanine 78 on the left end of floor 76, or of proceeding up via up-ramp 81 to the mezzanine 78. Having reached the mezzanine 78, the option is to park on the mezzanine 78, to proceed up to the right end of floor 77 via the up-ramp 83 or down again to the right end 76' of floor level 76 via a down-ramp (not visible in Fig. 6). Exit from the right end 76' of floor 76 is by way of a down-ramp 82. Once on the right end of floor 77, the options are again to park (i. e. under the mezzanine 79), or

to proceed up to the mezzanine 78 via an up-ramp (also not visible in Fig. 6) at the far corner of the building. On mezzanine 78, the options are once more to park, to proceed downward to the left end 77' of floor 77 via the down-ramp 85, or to proceed up to the next floor (not shown) via an up-ramp 86. Exit from the left end 77' of floor 77 is by way of a down-ramp 84, and down-traffic from the next upper floor may flow to the mezzanine 79 via a down-ramp 81.

In applying my invention to the automatic routing of traffic in a garage such as shown in Fig. 6, counters need be provided again only to cover the independently accessible areas, and such routing may be obtained by considering the combination of a mezzanine and of one half of each floor as an independent parking area. For example, by considering the mezzanine 78 and the right half 76' of floor 76 as a unit, traffic can be first routed via the up-ramp 80, skirting the left end of the floor 76 to the up-ramp 81, at the top of which the left-arrow 88 will direct the motorist to seek parking space first on the mezzanine 78 or, failing such opportunity, to proceed down the down-ramp (not shown) back to the right half 76' of floor 76. Once having entered the mezzanine 78 in response to the instruction of the arrow 88, the in-counter 89 for the mezzanine-and-half-floor area 76'-78 is operated. The out-counter 90 for this area 76'-78 may be located at the head of the down-ramp 82. "In" and "out" counters 89 and 90 may cooperate with suitable computer means (similar to that shown in Fig. 3) whereby the arrow 88 is extinguished and the arrow 91 illuminated when the half-floor 76' and mezzanine 78 have been filled to capacity. Presumably, the left half of floor 76 will have been filled before motorists begin to seek upper-level parking space via ramp 81. Illumination of the arrow 91 will mean a directing of traffic up the up-ramp 83, to skirt the far or right side of the floor 77, and to proceed up the up-ramp (not shown) at the far corner of the building to the mezzanine 79. At the head of this up-ramp (not shown) stands a system of traffic-control arrows or other indicator means 92 similar to that which has just been described for the half-floor and mezzanine 76'-78. It will be understood that when the half-floor and mezzanine 77'-79 have been filled to capacity, as determined by the computer associated with the in-counter 93 and the out-counter 94, traffic will be routed to the next higher half-floor (at the left end of the building) via the up-ramp 86.

In order that exit-bound traffic descending from upper floors will not disrupt the computing functions which have been described for floors 76-77 and for mezzanines 78-79, the out-counters 94 and 90 may also be connected to perform in-counting functions. For example, exit-bound traffic descending down-ramps 87 and 85 to the half-floor 77' crosses counter 94 just before descending down-ramp 84. In descending down-ramp 84, these vehicles are really entering the parking area 78-76'; and, inasmuch as they will be counted "out" by the out-counter 90, they should also be counted "in" by the counter 94. For this reason, it is desirable that counter 94 perform the dual function of supplying out-counting impulses to the computer-indicator system for the area 79-77' and of supplying in-counting impulses to the computer-indicator system for the area 78-76'. In like manner, it will be understood that the out-counter (not

shown) for the parking area immediately above mezzanine 78 supplies in-counting impulses for the computer-indicator system for the area 78-77'; while the out-counter 90 for the area 78-76' supplies in-counting impulses for the computer-indicator system for the parking area (not shown) immediately below floor-level 76.

It will be appreciated that I have disclosed an improved means for the automatic handling of vehicular traffic in a garage. As applied to a plurality of garage types, the invention makes possible efficient "self-parking." The system is fully automatic while the garage is loading and while vehicles are leaving, and it may be so designed that new customers will always be routed to the lowest level on which there is available space (assuming such to be the desired method of handling traffic).

While I have described my invention for the preferred forms shown, it will be understood that modifications may be made within the scope of the claims which follow.

I claim:

1. In a garage system of the character indicated, first counting means for counting vehicles entering a given area, second counting means for counting vehicles leaving said area, differential means for resolving the difference between operations of both said counting means, and indicator means responsive to said differential means, said indicator means including means directing traffic into said area for differential operations less than substantially a given number and means directing traffic away from said area for differential operations greater than substantially said given number.

2. In a garage or the like, first means for counting vehicles entering a given area, second counting means for counting vehicles leaving said area, differential means for resolving the difference between operations of both said counting means, and indicating means responsive to said differential means, and including means directing traffic away from said area upon attainment of a given differential between operations of said counter means.

3. In a garage or the like, two parking areas, first counting means for counting vehicles entering the first of said areas, second counting means for counting vehicles leaving said first area, differential means for resolving the difference between operations of both said counting means, and indicating means for directing traffic to said second parking area upon attainment of a given differential between operations of said counter means.

4. In a garage or the like, two independently accessible areas, indicator means located at the parting of routes to said two areas for routing vehicles to the first of said areas, first counting means for counting vehicles entering said first area, second counting means for counting vehicles leaving said first area, computing means responsive to both said counting means and connected to said indicator means for routing traffic to said second area upon attainment of a predetermined differential between operations of said counting means.

5. In a garage or the like, two parking areas, first counting means for counting vehicles entering the first of said areas, second counting means for counting vehicles leaving said first area, differential means including a first driven element responsive to said first counting means, a second driven element responsive to said sec-

ond counting means, and a differential element coupled to said first and said second elements, and indicating means responsive to a given operation of said differential element for routing traffic to said second area.

6. In a garage or the like, two parking areas, a first counting device located at the entrance to the first of said areas and producing an electric signal for each object passing said entrance, a second counting device located at the exit from said first area and producing an electric signal for each object passing said exit, differential means for resolving the difference in operations of said counting devices and including solenoid-actuated ratchet means coupled to the outputs of each of said counting devices, and indicating means responsive to the differential derived from said differential means for routing traffic to said second area upon attainment of a predetermined differential between operations of counting devices.

7. In a garage having a plurality of parking levels and ramps communicating with said levels, indicating means for routing traffic to one of said levels, first counting means for counting the number of vehicles entering said first level, second counting means for counting the number of vehicles leaving said level, computing means for resolving the difference between operations of said counting means, and means connected to said computing means and to said indicating means for directing traffic away from said first level and to another level upon attainment of a predetermined differential in the operation of said computer means, whereby parking may be efficiently completed on said first level before parking on said second level is begun.

8. In a garage having a plurality of parking areas, first counting means for counting all vehicles to enter said garage, second counting mean for counting all vehicles to leave said garage, third counting means for counting vehicles in one of said areas, differential-indicating means responsive to the difference in operations of said third counting means and of one of said first two counting means for routing traffic away from said first area and to a second area, and differential-indicating means for resolving the difference between operations of said first and said second counting means.

9. In a garage having a plurality of parking areas accessible from a single entrance and communicating to a single exit, a first counting device for counting vehicles entering said garage, a second counting device for counting vehicles

leaving said garage, a third counting device for counting vehicles entering one of said areas, differential-indicating means responsive to the difference between operations of said third counting device and of said second counting device for commanding a change in the flow of traffic in said garage, and differential-indicating means responsive to the difference in operations of said first two counting means for indicating when said garage has been filled to capacity.

- 5 10. In a garage having a plurality of parking areas accessible from a single entrance and communicating with a single exit, a first counter for counting vehicles entering said garage, a second counter for counting vehicles leaving said garage, and a third counter for counting vehicles leaving one of said areas to the exclusion of another of said areas, indicator means for routing vehicles into said one area, computer means for resolving the difference between operations of said first and said third counters, said computer means including means coupled to said indicator means for routing traffic away from said one area and in the direction of a second area upon attainment of a predetermined differential by said computer means, and further computer means responsive to the difference in operations in said first and said second counters for indicating when said garage has been filled to capacity.
- 15 11. In a garage or the like having a plurality of parking areas, some of said areas being accessible independently of other areas, and further of said areas being dependent upon other areas for accessibility, each of said independently accessible areas including in-counter means for counting vehicles entering each said independent area, out-counter means for counting vehicles leaving each said area, computer means for resolving the difference between the counts of both said counter means, and an indicator for routing traffic away from each said independent area when said computer means determines that each said independent area is loaded substantially to capacity.
- 20 25 30 35 40
